UNITED STATES PATENT OFFICE

ROLLAND T. CASE, OF LA CROSSE, WISCONSIN

TOOTHBRUSH CONTAINER

Application filed March 3, 1930. Serial No. 432,798.

This invention relates to containers and holding devices for small articles and while adapted for wide general use, is especially applicable for holding and rendering conveniently accessible a plurality of articles which it is desirable to use successively, such as for example, tooth brushes.

Authorities on dental hygiene at this time strongly recommend the successive use of a plurality of tooth brushes varying in shape, structure and sometimes size, in order that the variously shaped teeth and interproximal spaces may be properly cleansed and further in order that the brushes may be thoroughly dried and stiffened before again being used.

It is an object of my invention to provide a simple and highly efficient container for holding and housing a plurality of articles such as tooth brushes and for rendering the same conveniently accessible.

It is a further object to provide in a container of the type above described, an automatic indicator progressively operated by the removal of the articles in the container to indicate the article which is to be next used.

Another object is to provide in a container for articles such as tooth brushes, a series of article holders, which will receive only specially constructed articles, whereby generally similar articles of another manufacture will be excluded therefrom.

Still another object is to provide in a container for a plurality of articles, article engaging and holding means for a series of specially constructed articles varying in size, shape or form, so constructed and associated that each article holder will receive only a certain make, type or shape of article, thereby requiring always the placing of a certain article upon a certain holder.

Another object is to provide a cabinet which may comprise a series of unit containers mounted upon a suitable panel or plate and removable therefrom when desired.

Still another object is to provide a decorative and highly efficient cabinet, the compartments or containers of which are adapted to be inset within a wall and provided with efficient ventilation through the panel or face of the cabinet.

Another object is to provide a holder or container for a number of tooth brushes, having therein an indicating device progressed automatically by the withdrawal of the tooth brushes from the container, the holding elements of the device being so constructed that the articles must be swung to remove the same from the container thereby progressively actuating the indicator.

These and other objects and advantages of the invention will be fully set forth in the following description made in connection with the accompanying drawings, wherein like reference characters refer to similar parts throughout the several views, and wherein

Fig. 1 is a front elevation of a tooth brush cabinet embodying my invention, comprising a panel, whereon are mounted a plurality of removable unit containers;

Fig. 2 is a top plan view of the same; 70

Fig. 3 is a vertical section taken on the line 3—3 of Fig. 1;

Fig. 4 is a front elevation of one of the tooth brush containers detached, the door being partially broken away; 75

Fig. 5 is a vertical section taken on the line 5—5 of Fig. 4;

Fig. 6 is a cross section taken on the line 6—6 of Fig. 5;

Fig. 7 is a cross section on an enlarged scale 80 taken on the line 7—7 of Fig. 4;

Fig. 8 is a vertical section taken on the line 8—8 of Fig. 7; and

Fig. 9 is a vertical section taken through a removable unit container for tooth paste. 85

As shown in the drawings, each of my tooth brush containers comprises a rectangular box casing 10 having an open front and a top and bottom 10a and 10b respectively, each provided with a series of relatively large ventilation apertures 11. The interior of casing 10 is divided longitudinally by means of divider plates 12, into a series (as shown three) of article holding chambers C, each adapted to contain a tooth brush. Plates 12 extend from the bottom of casing 10 to points spaced some distance from the top thereof. An article holding element, preferably in the form of a fin 13 is disposed medially and longitudinally of each of the cham-

- bers C being secured to the rear side of casing 10. Each of the fins 13 is provided at its upper edge with a notch 13a adjacent the outer longitudinal edge thereof forming a hook 13b and a fulcrum 13c for retaining a specially constructed article, such as a tooth brush B. Fins 13, as shown, extend from the upper ends of the dividing plates 12 to the medial portions thereof. The lower edges of 10 said fins are curved substantially concentric with points 13c which constitute the fulcrums for removal of the tooth brushes, as hereafter will be more clearly shown. Each of the fins 13 is provided with an arcuate corrugation X on one face thereof, the corrugations extending concentrically with the respective fulcrum points 13c of the fins. The corrugations on the several fins may be located at different distances or radii from the 15 fulcrum points 13c, for a purpose later to be explained.
- The tooth brush container 10 is provided with a hinged door 14, the hinges 14a being disposed in alinement with one of the longitudinal edges of the casing 10, so as not to protrude from the adjacent side wall of the casing. A spring latch 14b may be provided for retaining the door in closed position and a door handle or knob 15 is also provided.
- 20 Mounted within the top portion of my container is an indicating device, automatically operated by the removal of the brushes from the casing to indicate the next brush which is to be used. This indicator comprises a small cylinder 16 rotatably mounted in a horizontal sleeve 17 which may be spot welded or otherwise secured to a small bracket 17a attached to the top 10a of the casing. The sleeve 17 is provided with a series of horizontally alined sight openings 17b at the front thereof, one being provided for each of the tooth brushes or articles held in the compartment C, and located directly thereabove. A ratchet wheel 18 is fixed to one end of cylinder 16 and has a diameter substantially equal to the diameter of sleeve 17. Ratchet wheel 18 is provided, as shown, with six teeth and is operated by a pawl 19 attached to one end of a trip plate 20, which extends outwardly of 25 and below sleeve 17 and substantially parallel with the axis of said sleeve. Trip 20 is provided with upturned arms 20a, which may be pivoted to pins 16a provided at the ends of cylinder 16. A small abutment member 21 may be secured to the rear wall of casing 10 to limit the rearward swinging movement of the trip plate. One of the arms 20a is connected by a coiled spring 22 with a screw or pin 22a secured adjacent the forward edge 30 of the top 10a of the casing, said spring normally holding the trip plate in upwardly swung position. Assuming the body of cylinder 16 divided into three imaginary zones, each alined with one of the sight openings 17b, in sleeve 17, a pair of enameled or colored

dots or other indicia 23 are provided for each zone arranged diametrically opposite one another. The dots for the successive zones are staggered at sixty degree angles, whereby each sixth rotation of the cylinder will successively position one of the dots or indicating elements in registration with one of the viewing apertures at the front of sleeve 17. 70

Between two of the said zones a series of six circumferentially spaced recesses 17c are 75 provided adapted to be successively engaged by a spring pressed retaining element 24, which may be conveniently attached to the exterior of sleeve 17 and which, as shown, has a ball engaging head working through an 80 aperture in said sleeve.

The unit container may be provided on its rear wall with a pair of outwardly projecting attachment bosses 10c which are adapted to interlock with key-hole slots 85 formed in a supporting bracket 26, which as shown, is suitably secured to a wall.

The embodiment of the invention illustrated constitutes a tooth brush container or cabinet and the compartments C and fins 13 90 are formed to receive and hold only specially constructed tooth brushes. The handles of my tooth brushes are of such width as to nicely fit the width of the compartments and each handle is provided with an elongated slot 27 extending longitudinally thereof and of proper length to accommodate one of the fins 13. The slots of the several brushes are each provided with a laterally extending enlargement or notch 27a for accommodating a corrugation on one of the fins. As illustrated, each of the brushes B has a differently shaped brushing surface and a differently positioned notch or enlargement 27a, corresponding to the position of the corrugation on one of the fins only. Each brush in the form of the invention shown, therefore, may only be held in one certain compartment and will be excluded from the others. 100

In Fig. 9 a unit container for tooth paste or a mouth wash is shown comprising an oblong-shaped casing 30 having a door 30a in the front face thereof, the hinges of said door being alined with one of the longitudinal edges of the side walls. 110

While my several unit containers are adapted to be used independently they are also specially adapted to be detachably connected to a suitable panel or frame, such as is shown in Figs. 1 to 3, inclusive to constitute a highly decorative cabinet. A panel or plate P which may be constructed from sheet metal is provided with a series of symmetrically arranged openings 32 therein of proper dimensions to accommodate the container units. At the upper and lower edges of the openings 32, flanges 33 are inturned disposed at right angles to the face of the panel and the top and bottom of the casings 10 and 30 may be de- 115 120 125 130

tachably connected thereto by suitable means, such as small screws 34 threadedly engaging the flanges 33 and being applied from the interior of the casing. The panel P illustrated, carries a pair of the unit containers 10 between which is mounted one of the tooth paste containers 30, the doors of said several containers being positioned substantially flush with the face of panel P to present a decorative appearance.

Panel P is provided with ventilation apertures 35 through the face thereof, one being disposed above the top of one of the tooth brush containers 10 and one being disposed below the same and inwardly extending ventilation cowls 36 are provided for each of the brush containers 10 and one being disposed through each of the tooth brush containers, apertures 35 cooperating with the bottom and tops of the containers in the manner shown in Fig. 3. The lower cowls 36 are inclined to deflect air properly through the bottom ends of the several container units, causes a draft of air to be set up through each of the tooth brush containers, thereby quickly drying the brushes and maintaining them in proper condition for use.

The lower cowls 36 are conveniently accessible from the face of the panel by merely swinging open the doors 14. The tooth brushes, or other articles, are as easily removed one of the containers 10, this may be quickly accomplished by releasing the screws 34 in the interior of the container and simply slipping the container outwardly through the door aperture 32 in the panel.

Operation.—The specially constructed brushes are inserted upon their respective holding fins by inserting the handle end of the brush in upwardly inclined position, as shown in Fig. 5, engaging the upper end of the slot 27 of the brush with the hook 13b and the point 13c and is guided by the curved edge of the slotted portion 13a which is disposed concentric with said point. The extremity of the handle on the brush inserted will slip outwardly past the trip lever.

To remove a brush, the upper end of the handle is pressed inwardly usually by the forefinger, engaging the trip plate 20 and thereby swinging the plate rearwardly to actuate the indicator through the connection of pawl 19 with one of the teeth of the ratchet wheel 18. This brings a dot or other indicator in registration with one of the side openings 17b which is disposed above one of the brushes and shows the owner of the cabinet that the brush below the indicator is to be next used. When a brush is swung outwardly by depressing the upper end of the handle, the lower portion of the brush will be projected in inclined position through the opening 17b in front of the casing and may be grasped in the hand and removed.

In the embodiment of the invention illustrated, each brush may be received by only one of the holding fins 13 due to the special arrangement of notches 27a of the brushes and the corrugations X on fins 13. In the operation of the indicator, the spring pressed retainer 24 prevents the indicator cylinder 16 from slipping past the proper points of alinement controlling the progression of the cylinder for each tripping of plate 20. The structure disclosed in Figs. 1 to 3 inclusive, provides an ornate cabinet, the holding device or containers of which are housed with in a recess in a wall. My improved ventilation structure, comprising the cowls 36 in cooperation with the apertured top and bottom ends of the several container units, causes a draft of air to be set up through each of the tooth brush containers, thereby quickly drying the brushes and maintaining them in proper condition for use.

The tooth brushes, or other articles, are as easily removed one of the containers 10, this may be quickly accomplished by releasing the screws 34 in the interior of the container and simply slipping the container outwardly through the door aperture 32 in the panel.

This permits the container to be utilized when traveling, without removal of the panel from the wall.

From the foregoing description, it will be seen that I have provided an ornate and compact container and cabinet for tooth brushes.

35 downwardly, the slot 27 accommodating the fin and the particular notch or enlargement 27a of the slot accommodating the corrugation X on the particular fin designed to receive the brush. The brush is fulcrumed on the point 13c and is guided by the curved edge of the slotted portion 13a which is disposed concentric with said point. The extremity of the handle on the brush inserted will slip outwardly past the trip lever.

40 To remove a brush, the upper end of the handle is pressed inwardly usually by the forefinger, engaging the trip plate 20 and thereby swinging the plate rearwardly to actuate the indicator through the connection of pawl 19 with one of the teeth of the ratchet wheel 18. This brings a dot or other indicator in registration with one of the side openings 17b which is disposed above one of the brushes and shows the owner of the cabinet that the brush below the indicator is to be next used. When a brush is swung outwardly by depressing the upper end of the handle, the lower portion of the brush will be projected in inclined position through the opening 17b in front of the casing and may be grasped in the hand and removed.

45 It will be understood that various changes may be made in the form, details, arrangement and proportions of the parts without departing from the scope of my invention, which, generally stated, consists in the novel combination of parts described in the specification and set forth in the appended claims.

What is claimed is:

50 1. In an article holder, a receiving compartment in the form of a vertical channel, elongated retaining element projecting

55 from the top and bottom ends of the compartment, the element being curved to receive an article.

50 60 65

- from the rear of said channel and extending longitudinally and medially of said channel and an article of slightly less width than said compartment and having a longitudinal slot 5 accommodating said retaining element, whereby articles of other construction will be excluded from said compartment.
2. In an article holder, a receiving compartment in the form of a vertical channel, a holding fin extending longitudinally and medially of said channel, said fin having an abutment shoulder, constituting a fulcrum at its upper end disposed inwardly of its longitudinal outer edge and spaced from the rear 10 of said compartment and a specially constructed article of slightly less width than said channel having a longitudinal slot accommodating said fin, top of said slot terminating at a point spaced below the upper end of said article, whereby said upper end may be pressed inwardly against said fulcrum to swing the lower portion of said article outwardly in position for removal.
3. In an article holder, a receiving compartment in the form of a vertical channel, a retaining fin projecting from the rear of said channel and extending longitudinally of and medially thereof, said fin having a hook-shaped upper end, an article of 15 slightly less width than said compartment having a longitudinal slot extending through a substantial portion thereof adapted to accommodate said fin, said slot terminating at a point adjacent the upper end of said article.
4. In an article holder, a receiving compartment in the form of a vertical channel, a retaining fin projecting from the intermediate side of said channel and extending longitudinally and medially of the sides of 20 said channel, said fin having an abutment shoulder at its upper end disposed inwardly of its longitudinal outer edge and outwardly from the rear of said channel, and a specially 25 constructed article of slightly less width than said compartment having a longitudinal slot accommodating said fin, said fin having a projection on one side thereof which extends concentrically of said shoulder, said article having an enlargement in said slot positioned to accommodate said projection.
5. In an article holder, a casing having a door in the front thereof, a vertical retaining fin projecting from the rear side of said casing having a hook-shaped upper end provided with an abutment shoulder constituting a fulcrum at the rear of the hook, said fulcrum being spaced from the rear side of said casing 30 said fin being adapted to accommodate a specially constructed article having an elongated slot therein, which slot terminates at a point below the upper end of the article to permit the article to be swung on said fulcrum, projecting its lower end through the doorway 35 of said casing to facilitate removal.
6. In an article holder, a vertically disposed retaining fin, having a shoulder at its upper end disposed inwardly of the forward longitudinal edge thereof, and a curved edge disposed forwardly of said shoulder and concentric with the point of said shoulder, a narrow bulge extending transversely of said fin and curved concentrically with the point of said shoulder, said fin being adapted to receive and retain a specially constructed article having an elongated slot adapted to accommodate said fin, said slot terminating at a point below the upper end of said article, and said slot having a lateral notch or enlargement disposed to accommodate said bulge. 70
7. Exclusive retaining means for an article of manufacture, comprising a handle or analogous elongated member having therein a longitudinally extended slot which terminates at a point spaced some distance from one end of said handle or member, said slot being adapted to accommodate a complementary-shaped projecting element which is provided with a fulcrum adjacent its upper end, the portion of said handle or member disposed outwardly of the end of said slot constituting a lever arm whereby the article 75 may be swung for convenient removal.
8. In an article holder, a series of spaced article holding elements so constructed as to require articles to be moved through predetermined paths for attachment thereon and removal therefrom and an indicating mechanism mounted adjacent said holding elements and having an actuating element disposed adjacent said holding elements and in the paths of movement of said articles and a movable indicating element progressed by 80 said actuating element.
9. In an article holder, a casing having a series of spaced article holding elements mounted therein, said elements being adapted to interfit with apertured portions of specially constructed articles and having hook retaining portions and adjacent fulcrum shoulders at their upper edges upon the fulcrum points of which articles must be fulcrumed for removal from said elements, an indicating device mounted above said article holders and comprising a rotary cylinder and a trip plate extending below said cylinder in the path of said articles, a ratchet fixed to said cylinder and a pawl connected with said trip plate. 85
10. The structure set forth in claim 9, arcuately arranged guides on said article holding elements adapted to engage cooperating means on the apertured portions of said articles for determining the line of movement of said articles in removing the same from 90 said holding elements.
11. In an article holder, a casing having a series of spaced article holding elements mounted in side by side relation, said elements having retaining portions adjacent 95

their outer ends and fulcrum shoulders immediately adjacent said retaining portions, about which shoulders, articles must be swung for removal, an indicating device mounted above said article holders and having a reciprocal actuating or striker element extending just above all of said shoulders and disposed in the path of swinging of said articles and a rotary indicating element mounted in said indicating device and progressed by the movement of said actuating or striker element.

In testimony whereof I affix my signature.
